UNITED STATES PATENT OFFICE

LOUIS H. WELLENSIEK, OF HOUSTON, TEXAS, ASSIGNOR TO HUGHES TOOL COMPANY, OF HOUSTON, TEXAS, A CORPORATION OF TEXAS

CORE CATCHER FOR WELL DRILLS

Application filed May 13, 1929. Serial No. 362,645.

My invention relates to means for engaging the core in a core drill so that the core may be broken off and withdrawn with the drill when the drill is removed from the hole.

5 This device is an improvement upon that shown in my prior co-pending application No. 331,526, filed January 10th, 1929.

The invention has for its object, the provision of a positively movable means to seize 10 the core, said means being operated by the upward pull of the drillstem.

I desire to provide a means for operating the core engaging dogs, which is free and unobstructed and not liable to be clogged in 15 use.

It is a further object to simplify the structure of the device set out in my prior application previously referred to, and to make the device more economical to construct and 20 reliable in use.

The invention resides largely in the particular construction and arrangement of the parts making up my improved device.

25 In the drawings, Fig. 1 is a central longitudinal section through a drill and core barrel employing my invention.

Figs. 2, 3 and 4 are transverse sections taken on the planes 2—2, 3—3, and 4—4, respectively of Fig. 1.

30 The core drill with which my invention is employed may be of any desired construction. I have shown a bit comprising a head 1, having a central threaded socket 2 at its upper end about the core passage 3, to receive the shank 4 of a special drill nipple 5. The bit has lateral blades 7 to cut the well hole. Flushing fluid reaches the cutters through 35 passages 8 in the head.

40 The nipple 5 is a tubular member extended upwardly a suitable distance. Its inner diameter is increased slightly at 9 to provide a shoulder, below which the inner wall is threaded to receive a core barrel 10 screwed therein.

45 Adjacent the lower end of the nipple 5, is a plurality of radial openings 11, in which are fitted housings 12 for the core-engaging dogs 13. Said housings fit closely in the openings, as seen in Fig. 2, and are adapted to be locked therein by set screws 14, one on each

side of each housing. Each housing 12 has mounted therein, a transverse pin 15, upon which a dog 13 is rotatable.

Said dogs are nearly semicircular blocks fitted within slots in said housings, the rounded side being presented outwardly, and provided with central slots 16 therein to receive the lower ends of rods 18. Transverse pins 17 through said dogs and the ends of said rods 18 provide a pivotal engagement between them. The dogs have their inner faces 19 curved transversely to some extent, as shown in Fig. 2, to better engage the core when they are projected inwardly.

The rods 18 are actuated through a drill 55 collar 20 which telescopes over the nipple 5 and is slidable on said nipple. The upper end of the collar 20 has a threaded socket 21 to engage a tool joint on the drill stem. Its lower end 22 has a plurality of longitudinal 60 slots 24 therein to receive the upper ends of the rods 18; the lower ends of the slots having guide openings 25 therein to allow passage of said rods. The rods 18 have nuts 26 at their upper ends and a compression spring 70 27 on each of said rods bears at its upper end against said nut and at its lower end upon a washer set upon the lower end of the slot 24.

The drill collar 20 is connected with said 75 nipple 5 by means of radially projecting pins 28 screwed within the nipple and projecting outwardly into slots 29 in the drill collar. I have shown four sets of pins with two pins 80 28 in each set, as forming the connection 85 between the two telescoping parts. The slots 29 are longer than the distance between each pair of pins 28 so as to allow a predetermined amount of play of the collar longitudinally of the nipple.

The upper end of the nipple forms a practically fluid tight sliding connection with the collar through the use of a ring 30 of composition fitting within a recess in the drill collar and projecting within a recess 31 in the nipple. 95 For purposes of assembly grooves 32 longitudinally of the nipple are formed to allow the rod and spring 18 and 27 to be moved downwardly over the said nipple. The pins 28 may be held from unscrewing by the use 100

of a key or bar 33 fitting within aligned slots in the end of each set of said pins. The outer edges of said slots are peened over to retain said key.

5 In the use of my device the tool is assembled as shown in Fig. 1 and when the bit and nipple 5 are suspended from the drill collar and drill stem while going into the hole, the dogs 13 will be approximately in the position illustrated. When the drill rests upon the bottom, however, the drill collar will slide down on the nipple to bring the pins 28 into the upper end of the slots 29 so that the weight of the drill collar and drill stem will rest upon the drill. This movement of the collar downwardly upon the nipple will release the upward tension upon the springs 27 and will allow dogs 13 to rotate into a position with their inner faces parallel with the inner wall 20 of the core barrel.

The rotation of the drill stem will then be communicated through the pins 28 to the nipple and drill and the hole will be cut and a core will gradually project upwardly into 25 the core barrel. When it is desired to bring the core to the surface the drill will be withdrawn. The upward movement of the drill collar will bring the pins 28 to the bottom of the slots 29 as shown in Fig. 1, and will exert 30 a compression upon the springs 27 to pull the rods 13 upwardly and move the core engaging dogs into the position shown, the dogs then being brought into contact with the core. If the core is of soft material, the dogs will 35 penetrate the core to the dotted line position in Fig. 1, but where the core is hard, it will not penetrate so deeply. This will break off the core and carry it along with the core barrel.

40 It is to be noted that the pull upon the rods to move the dogs is entirely through the springs 27 and there will be no danger of too great a pull upon the rods whereby they might be broken or the nuts 26 stripped from 45 the rods as might otherwise happen. Furthermore, in this embodiment, the parts are easily accessible for assembly or disassembly when necessary. The springs and rods 27 and 13 are exposed so that they may be washed 50 clear of sand or mud tending to clog their action.

What I claim as new is:

1. A core bit, an upwardly extending nipple thereon, a drill collar telescoping over 55 said nipple, radial pins on said nipple projecting into openings in said drill collar, and having a limited longitudinal play therein, core engaging dogs in said nipple, and means on said collar adapted to engage said dogs to 60 move them into core-engaging position.

2. A core bit, an upwardly extending nipple thereon, a drill collar telescoping over said nipple, radial pins on said nipple projecting into openings in said drill collar, and having 65 a limited longitudinal play therein, core en-

gaging dogs in said nipple, operating rods on said dogs, and resilient means on said collar, engaging said rods to move said rods and said dogs.

3. In a core drill, a bit, a nipple thereon, 70 a drill collar engaging telescopically over said nipple, a radial pin on said nipple projecting into a slot in said collar to allow a limited longitudinal movement of said collar relative to said nipple, core-engaging dogs in said nipple, and resilient connections between said collar and said dogs, whereby the movement of said collar relative to said nipple may move said dogs.

4. In a core drill, a bit, a nipple thereon, 75 a drill collar engaging telescopically over said nipple, a radial pin on said nipple projecting into a slot in said collar to allow a limited longitudinal movement of said collar relative to said nipple, core-engaging dogs in said nipple, rods on said dogs projecting into said collar and springs on said rods engaging said collar, whereby the movement of said collar relative to said nipple may move said dogs.

5. In a core drill, a drill head, a nipple connected therewith, core-engaging dogs in 85 said nipple pivotally mounted in said nipple, means to rotate said nipple and bit, and means on said rotating means resiliently connected with said dogs, the weight of said rotating means acting to hold said dogs depressed, whereby said dogs may be pivoted to move inwardly to engage the core when 90 said rotating means is moved upwardly.

6. In a core drill, a drill head, a nipple connected therewith, core engaging dogs in said nipple pivotally mounted in said nipple, means to rotate said nipple and bit, and means on said rotating means resiliently connected with said dogs, whereby said dogs may be pivoted to move inwardly to engage the core, said dogs being actuated by the relative longitudinal movement of said rotating 105 means.

7. In a core drill, a drill bit, a tubular nipple thereon, a drill collar telescoping over said nipple; a plurality of radial pins detachably mounted in said nipple and projecting into slots in said drill collar to allow a limited longitudinal play between said nipple and said collar and means actuated by said longitudinal movement of said collar relative to said nipple to move inwardly to engage the core.

8. In a core drill, a drill bit, a nipple thereon, a drill collar telescopically engaging said nipple to communicate a rotation thereto, core engaging dogs pivotally mounted in said nipple to move inwardly to engage the core, rods on said dogs slidably engaging said drill collar, and springs on said rods adapted to be compressed to exert a pull on said rods.

9. In a core drill, a drill bit, a nipple there-

on, core engaging dogs in said nipple, a drill collar telescopically engaging said nipple, said collar having longitudinal slots therein, pins adapted to be inserted through said slots 5 to engage within said nipple, and means on said collar engaging said dogs to move said dogs in said nipple.

10. In a core drill, a drill bit, a nipple member thereon, a collar member telescopically engaging with said nipple member, means engaging said nipple and collar together to allow a limited play longitudinally between them, core engaging dogs on one of 15 said members, and means on the other said member resiliently connected with said dogs to move said dogs into core engaging position.

11. In a core drill, a drill head, a drill collar telescopically engaged therewith to drive 20 said drill head and having a limited longitudinal movement relative thereto, dogs pivoted on axes transversely of said head, means on said collar engaging said dogs to cause them to pivot on their axes when said collar 25 is moved longitudinally relative to said head, so as to move said dogs to and from core engaging position.

12. In a core drill, a head member and a 30 drive collar member having a limited telescopic movement longitudinally and held against rotation relative to said head member, and core engaging dogs normally housed in one of said members, but adapted to be 35 projected into core engaging position by the upward movement of said collar member relative to said head member while said head member is stationary.

13. In a core drill, a drill head, a drive 40 collar connected to drive said drill head, but having a limited longitudinal play without rotation relative to said head and core engaging means normally retracted, but connected to said collar so as to be projected into core 45 engaging position by the vertically upward movement of said collar relative to said head while said head is stationary.

14. In a core drill, a drill head, a drive 50 collar connected to drive said drill head, but having a limited longitudinal play relative to said head, core engaging dogs pivotally supported on horizontal axes set in said head, and means connecting said dogs with said collar whereby said dogs are forced into core 55 engaging position by the relative vertically upward movement of said collar.

In testimony whereof I hereunto affix my signature this 10th day of May, A. D. 1929.

LOUIS H. WELLENSIEK.
